MERCAPTOSUCCINAMIC DERIVATIVES OF AMINOSTEROIDS

Harvey E. Alburn, West Chester, Norman H. Grant, Wynnewood, and Donald E. Clark, Norristown, Pa., assignors to American Home Products Corporation, New York, N.Y., a corporation of Delaware

No Drawing. Filed July 12, 1965, Ser. No. 471,402
4 Claims. (Cl. 260—397.1)

This invention relates to compositions of matter classified in the art of chemistry as mercaptosuccinamic derivatives of aminosteroids.

The claimed compositions reside in the concept of chemical compounds in which there is attached to the amino group of a 3-aminosteroid a 3-mercaptopsuccinamido group.

The claimed compounds possess the inherent general physical characteristics of being crystalline solids. These compounds possess the characteristic reactivity of mercaptans permitting selective formation of mixed disulfide steroids and sulfonic acid steroids. In addition, their alkali metal salts are quite water soluble. These characteristics taken together with the nature of the starting materials, their spectral data and the mode of synthesis positively confirm the structure of the claimed compounds.

As determined by recognized and accepted pharmacological test procedures the claimed compounds exhibit pharmacological activity as antimicrobial and antilipemic agents.

The manner and process of making the invention will now be described so as to enable persons skilled in the art of chemistry to make and use the same as follows:

The preferred starting materials for the compounds of this invention are funtumine and funtumidine.

The preparation of the claimed compounds is illustrated as follows:

where

2

The reaction depicted herein above is carried out by reacting S-acetylmercaptopsuccinic anhydride (I) with a selected aminosteroid (II). This reaction preferably is carried out in an inert solvent such as dioxane and at room temperature. Following removal of the solvent, the residue from the reaction is treated with a nucleophilic agent such as hydroxylamine or hydrazine to give the final product.

The process of the invention also can be carried out with the following starting materials: 3-aminopregnanes such as holamine, holaphyllamine, holaphylline, paravallarine; 20-aminopregnanes such as funtuphyllamine A, funtuphyllamine B, funtumafrine B, holafebrine; and compounds of the holarrhime group such as holarrhidine, holarrhime, (3)-N-methylholarrhime, and (20)-N-methylholarrhime. Further details on these compounds appear in J. Pharmacy and Pharmacol. 14,469 (1962).

It will be readily appreciated from the nature of the starting compounds listed above that these may be substituted anywhere along the nucleus by simple substituents such as halo (lower) alkyl, lower alkoxy and the like. Similarly, substituent X may be an acetyl, hydroxyethyl, acetylamino or an amino group. Obviously, where X is an amino group, a second acyl group may be introduced into the molecule giving the bis-compound. The presence of the foregoing substituents on the molecule of the claimed compounds does not interfere with the desirable pharmacological properties of the corresponding unsubstituted compounds. The substituted compounds are full equivalents of such compounds and can be used for the same purposes.

The claimed compounds can, if desired, be converted into their non-toxic alkali metal salts by conventional techniques. The following examples illustrate the best mode of producing the invention:

Example 1.—N-(17β-acetamido-5α-androstan-3α-yl)-3-mercaptopsuccinamic acid

A mixture consisting of 3 grams of 17β-acetamido-3β-amino-5α-androstan-3α-yl, 1.57 grams of S-acetylmercaptopsuccinic anhydride, 1.25 ml. of triethylamine, and 150 ml. of dioxane was allowed to stand at room temperature for 2 weeks. The solvent was removed by evaporation. The residue was dissolved in water and treated with 5.1 ml. of 2 M hydroxylamine hydrochloride, followed by adjustment to pH 10.0. After stirring for 5 minutes the mixture was adjusted to pH 1.5 and filtered. The insoluble product was thoroughly washed with water and dried under vacuum, giving 3.4 grams.

The product is active against NWS Influenza virus and against B. subtilis 6633.

Example 2.—3α-(3-mercaptopsuccinamido)-5α-pregn-20-one

A mixture of 700 mg. of funtumine, 384 mg. of S-acetylmercaptopsuccinic anhydride, and 1 ml. of pyridine in 25 ml. of dioxane was stirred at room temperature. After 2 hours, 5.6 milliequivalents of NaOH was added, and the solution was allowed to stand for 20 minutes. It was then evaporated to dryness, and the solid was dissolved in water, acidified with 1.5 ml. 4 N HCl, and filtered. The insoluble portion was thoroughly washed with water, then dissolved in 50 ml. of water with addition of alkali to pH 9.5, filtered and precipitated again by adding excess HCl. After washing with water, the product was dried under vacuum at room temperature.

Example 3.—N,N'-(5α-androstan-3α, 17β-diyl)bis(3-mercaptopsuccinamic acid)

A mixture of 2 grams of 5α-androstan-3α, 17β-diamine, 2.4 grams of S-acetylmercaptopsuccinic anhydride, 1

ml. of triethylamine, and 100 ml. of dioxane was stirred for 3 hours at room temperature. Another ml. of triethylamine was added and the mixture allowed to stand 17 hours. There was then added 15 ml. of previously neutralized 1 M NH_2OH , and the mixture was stirred for 15 minutes and then evaporated nearly to dryness. 100 ml. of water was added, and the mixture was filtered. The filtrate was adjusted to pH 1.2 with 6 N HCl and the precipitate collected. It was suspended in water, brought to pH 9, refluxed with carbon, and filtered. The filtrate was acidified to pH 1.2, and the precipitate was collected and dried. The product was extracted into hot ethanol, and the solvent was removed under vacuum. The solid was washed with water and dried over phosphorous pentoxide, giving 2.3 grams. The compound is active in lowering blood lipids and is active against NWS Influenza virus.

Example 4.— 3α -(3-mercaptopsuccinamido)- 5α -pregnan-20 α -ol

A mixture of 3.4 grams of funtumidine and 1.85 grams of S-acetylmercaptopsuccinic anhydride was allowed to stand at room temperature. After 24 hours and 42 hours, 11 ml. aliquots of 1 N NaOH were added. The test for hydroxamic acid formation was now negative, and the suspension was evaporated to dryness. The solid was ex-

tracted with hot ethanol and the extract passed through a Dowex-1 (OH) column. The effluent and wash were pooled and filtered. The filtrate was evaporated to dryness, the solid was washed with water and then extracted into 25 ml. of dioxane. The extract was then evaporated to dryness, giving 1.85 grams of product.

The claimed compounds either in the form of their free acids or in the form of their alkali metal salts may be combined with conventional pharmacological diluents and carriers to form usual dosage forms.

10 What is claimed is:

1. $\text{N} - (17\beta\text{-acetamido-}5\alpha\text{-androstan-}3\alpha\text{-yl})$ -3-mercaptopsuccinamic acid.
2. 3α -(3-mercaptopsuccinamido)- 5α -pregnan-20-one.
3. $\text{N},\text{N}' - (5\alpha - \text{androstan-}3\alpha,17\beta\text{-diyl})$ bis(3-mercaptopsuccinamic acid).
4. 3α -(3-mercaptopsuccinamido)- 5α -pregnan-20 α -ol.
